UNITED STATES PATENT OFFICE

2,662,755

CONCRETE MIXER

Chris Gerst, Detroit, Mich., assignor, by mesne assignments, to Le Roi Company, Milwaukee, Wis., a corporation of Wisconsin

Application December 11, 1951, Serial No. 261,100

18 Claims. (Cl. 259—161)

1

This invention relates to concrete mixers and has particular reference to the material charging and discharging provisions for transit mixers of the end loading and discharging type.

In mixers of this type the charging device or hopper is provided with a rotatable closure for sealing against the charging and discharging opening in the end of the mixing drum. Considerable difficulty has been experienced heretofore in connection with the bearing between such rotatable closure and the hopper due principally to the fact that wet or dry mix gets into the bearing and quickly destroys the same. Numerous seal arrangements have been suggested to overcome this difficulty but they have not proven to be satisfactory in that they fail to exclude abrasive material from the bearing, with the result that the bearing has a relatively short life.

According to my invention the hopper, the rotatable closure carried thereby, and the bearing are constructed and arranged in such a manner as to prevent the mix, either wet or dry, from getting into the bearing, with the result that the life of the bearing is substantially prolonged.

In accordance with my invention, the bearing means between the hopper and the closure is constructed so that one of the joints of said bearing is exposed to the interior of the hopper, the other of the joints of the bearing is exposed to the outside of the hopper and the closure, and a labyrinth effect is provided between the bearing surfaces and the joint exposed to the interior of the hopper so as to exclude abrasive material from the bearing surfaces, the location of such joint so that it is exposed to the interior of the hopper further preventing wet mix from getting into the bearing.

A principal object of the invention, therefore, is to provide a new and improved charging and closure device for concrete mixers.

Another object of the invention is to provide a new and improved bearing construction for devices of this kind.

Other and further objects of the invention will be apparent from the following description and claims and may be understood by reference to the accompanying drawings, of which there are three sheets, which by way of illustration show preferred embodiments of the invention and what I now consider to be the best mode in which I have contemplated applying the principles of my invention. Other embodiments of the invention may be used without departing from the scope of the present invention as set forth in the appended claims.

2

In the drawings:

Fig. 1 is an end elevational view of a transit mixer embodying my invention;

Fig. 2 is an enlarged fragmentary elevational view of the closure device;

Fig. 3 is an enlarged fragmentary sectional view taken along the line 3—3 of Fig. 2;

Fig. 4 is a fragmentary sectional view taken along the line 4—4 of Fig. 2;

Fig. 5 is a fragmentary sectional view taken along the line 5—5 of Fig. 2;

Fig. 6 is a fragmentary sectional view similar to Fig. 3, showing a modification of the invention; and

15 Figs. 7, 8 and 9 are sectional views similar to Fig. 3 but showing modified forms of bearing structures between the hopper and the closure carried thereby.

As illustrated in Figs. 1 to 5 inclusive, a concrete mixer embodying my invention comprises in general a rotatable mixing drum 20 provided with an opening 22 at one end thereof through which material is charged into and discharged from the drum. An annular closure 24 is engageable with the drum 20 around the periphery of the opening 22 and is rotatable with the drum when so engaged as shown in Fig. 3. The closure 24 is movable away from the drum 20 so as to permit the discharge of material from the drum through the opening 22.

20 A material receiving hopper 26 on which the closure 24 is rotatably mounted is adapted to charge material through the opening in the closure 24 and into the drum through the opening 22 thereof when the closure is sealing the opening 22 in the drum, as shown in Fig. 3. The closure and hopper are supported for movement away from and toward the drum so as to permit discharging of the drum when the closure 24 is away from the opening 22, and to permit charging of the drum when the closure 24 is sealing against the end of the drum and closing the opening 22, as shown in Fig. 3.

25 Bearing means indicated generally at 28 are provided between the closure 24 and the hopper 26 to permit relative rotation therebetween when the closure is rotating with the drum, such bearing means being constructed so that one of the joints 30 thereof is exposed to the interior of the hopper and the other of the joints 32 thereof is exposed to the outside of the hopper and closure, this arrangement and location of the joints being important so as to exclude mix, wet or dry, from the bearing surfaces.

30 35 40 45 50 55 55 In mixers of the type to which the invention

pertains, the interior of the drum is provided with a series of axially and/or spirally extending blades 34 which during rotation of the drum 20 in one direction feed the material axially away from the opening 22 and serve to mix such material, and upon rotation of the drum 20 in the other direction about its axis serve to effect the discharge of the mixed material from the drum through the opening 22 thereof, the closure 24 at such time being away from the end of the drum 20 so as to expose the opening 22.

The drum 20 is journaled for rotation about its longitudinal axis and may be driven, for example, by the drive arrangement as shown in Gerst Patent No. 2,556,034, issued June 5, 1951.

As shown in Fig. 1, a pair of rollers 36 rotatably support the open end of the mixing drum 20 which is provided with a ring 38 which runs on the rollers 36 and thereby rotatably supports the open end of the mixing drum. The hopper 26 is provided with two arms or brackets 40, the outwardly projecting extremities 42 of which are mounted on arms 44 of a cross frame 46. The frame 46 is provided with two laterally extending tubular supports 48, each of which is supported by a series of rollers 50 carried by extensions 52 of the mixer frame, there being a series of rollers 50 on the extensions 52 both above and below the supports 48 so that the frame 46 is supported for movement in a horizontal direction and so that the closure 24 carried by the hopper 26 will move away from and toward the drum.

Actually, the supporting arrangement just described supports the closure 24 for movement along the axis of the drum 20 and with the axis of rotation of the closure 24 coinciding with the axis of rotation of the drum 20.

A hand wheel 54 connected to gearing 56 is arranged to operate a rock shaft 58 journaled in bearing 60 on the frame, the shaft 58 being provided with arms 62 which in turn are connected to links 64 carried by the frame 46 so that upon turning of the rock shaft 58 in one direction, the closure 24 and the hopper 26 will be moved away from the end of the drum 20 so as to expose the opening 22 thereof in order to permit discharging of the drum's contents, while upon rotation of the rock shaft 58 in the other direction the closure 24 will be moved so as to seat against the end of the drum and thereby seal the opening therein and thus position the hopper 26 so that material fed into the hopper will be charged into the drum 20 through the opening 22.

An adjustable link 65 connected to the hopper 26 and the frame 46 adjustably secures the hopper 26 relative to the frame 46 so that the plane of the closure 24 will be parallel with that of the end of the mixing drum 20. The mixer is also provided with chutes 66 positioned adjacent the opening 22 so as to direct material discharged therefrom into a discharge chute 68 adjustably mounted on the back of the mixer frame. The mounting of the chute 68 is disclosed and claimed in my copending application, Serial No. 257,486 filed November 21, 1951, now Patent No. 2,646,262, dated July 21, 1953, for "Discharge Chute Mounting for Concrete Mixers."

As shown in Fig. 3, the closure 24 comprises an annular disc-shaped ring or plate to the inside face 70 of which a gasket 72 is suitably secured, the gasket 72 being adapted to seat against and form a seal with a metal ring 74 welded or otherwise suitably secured to the end of the drum 20 so as to define the opening 22 therein.

As shown in Figs. 1 to 5, the hopper is provided with a flange 76 which is bolted or otherwise rigidly secured to a sealing ring or annular member 78. A bearing ring or annular bearing member 80 is rigidly secured to the ring 78 by a series of bolts 82, each of the bolts extending through an opening in the ring 78 and being threadedly secured in threaded holes in the bearing member 80. The annular closure 24 has rigidly secured within its central opening an annular bearing ring retainer 84 which is bolted to the closure 24 by a series of bolts 86. The ring or retainer 84 cooperates with a sealing ring 88 to define a cavity or chamber in which the bearing ring 83 is disposed, the ring 88 being rigidly secured to the ring 24 by a series of bolts 90. The inner peripheries of the rings 78 and 88 in addition form a part of the discharge hopper, and the ring 88 has secured thereto a cylindrical member 92 which forms a continuation of the hopper and which extends into the drum 20 beyond the ends of the blades 34 a substantial distance so as to discharge material fed into the hopper 26 into the drum at a distance inwardly away from the opening 22 in the drum. This arrangement not only facilitates charging and substantially reduces the charging time, but in addition the member 92 serves to exclude wet mix from the joint 30 between the rings 78 and 88. The member 92 is rigidly secured, such as by welding, to the ring 88, as shown in Fig. 3, and the interior surface of the member 92 forms a continuation of the hopper.

The rings 78, 80, 84 and 88 are so designed that the bearing surfaces are formed by outer peripheral cylindrical surfaces 94 and 96 of the bearing ring 80, and inner cylindrical surfaces 97 and 98 of the ring 84. In addition, the radially extending surfaces 100 and 102 of the ring 80, 104 of the ring 84, and 106 of the ring 88 form the thrust bearing surfaces of the bearing 28. The rings 78, 88, 80 and 84 are designed so as to provide a labyrinth effect indicated generally at 108 between the joint 30 and such bearing surfaces. In addition, the rings are made so as to provide annular grease pockets or channels 110, 112, 114, 116, 118 and 119 adjacent to the bearing surfaces.

As shown in Fig. 3, the rings 78 and 80 are provided with a duct 120 which communicates at one end with the grease pocket 116 and at its other end with a grease fitting 122 secured to the ring 78, whereby grease may be supplied to the bearing surfaces 94 and 96, 97 and 98.

As shown in Fig. 5, the rings 78 and 80 are provided with a duct 124 communicating at one end with the grease channel 114 and at the other end with a grease fitting 126, whereby grease may be supplied to the channel 114 and the adjacent grease channels not only for lubrication purposes but also for the purpose of excluding abrasive material from the bearing surfaces previously referred to.

As shown in Fig. 4, the ring 78 is provided with a duct 128 which communicates at one end with the grease channel 110 and at the other end with a grease fitting 130, whereby grease may be supplied to the channel 110 and to the joint 30 between the rings 78 and 88 so as to exclude dirt and foreign material from the bearing surfaces. Grease will also be supplied through the arrangement described to the clearances between the labyrinth effect 108 between the rings 78 and 88 so that this also will serve to exclude dirt and other foreign material from the bearing surfaces.

The joint 32, because it is exposed to the outside of the closure 24 and the hopper 26, is not exposed to grit and dirt as is the joint 30.

The parts 18 and 38 are so designed that the gap 30 therebetween is of the order of .016 in. and this gap is filled with grease from the fitting 130 which functions to exclude dirt and material from the bearing. In addition, the chute extension 92 functions as a baffle to exclude wet mix from the joint 30.

As the closure 24 rotates with the drum 20 when the closure 24 is in its closed position as shown in Fig. 3, the bearing 28 will be subjected to a cocking or distortion if there is any misalignment between the drum 20 and the closure 24. Due to the size of the parts and the load carried by the mixer and the jolting to which the mixer is subjected while in transit, it is impossible to always maintain the closure 24 aligned with the mixing drum 20, with the result that the bearing 28 is subjected to considerable loads. It will be noted that in the bearing construction as disclosed herein the bearing surfaces 94, 96, 97 and 98 are cylindrical surfaces which extend axially of the axis of rotation of the drum for a substantial distance, and this disposition of the bearing surfaces reduces to an appreciable extent the possibility of rapid wear on the bearing whenever misalignment may occur between the closure 24 and the drum 20.

To further reduce the effect of misalignment between the drum 20, the closure 24, and the bearing 28, the modified arrangement disclosed in Fig. 6 may be employed wherein the closure 24 instead of being bolted directly to the ring 84, as shown in Fig. 3, is secured to an annular ring 132 of rubber or other flexible and resilient material, which in turn is secured to the ring 84. Because of this, the closure 24 then will be free to move with the end of the drum 20 within limits without subjecting the bearing 28 to the effect of misalignment between the drum 20 and the closure 24.

In the modifications shown in Figs. 7, 8 and 9, the bearing construction embodies the same principle as that shown in Fig. 3, but the construction is simpler with a view toward economy in the cost of manufacture. In these modifications the same reference characters are used as previously used to indicate the same parts.

As shown in Fig. 7, the bearing is provided by two rings 150 and 152, the ring 150 being provided with cylindrical bearing surfaces 154 and 156, while the ring 152 is provided with cylindrical bearing surfaces 158 and 160. In addition, thrust bearing surfaces 162 and 164 are provided. The ring 150 is rigidly secured to the closure 24 by means of a series of bolts 166. Of course, the modification disclosed in Fig. 6 may be used in connection with any of the embodiments of the invention disclosed in this application. The ring 152 is rigidly secured by a series of bolts 168 to the hopper 170 corresponding with the hopper 26. In this case the flange 172 of the hopper 170 to which the ring 152 is secured is provided by a ring welded to the hopper chute 170. Adjacent portions of the ring 172 and the ring 150 define a gap or joint 174 which is exposed to the inside of the hopper, like the joint 30. The chute 92 is welded to the ring 150 and extends into the drum 70 as shown in Fig. 3. The rings 150 and 152 are provided with annular channels or grease pockets 176 and 178 which are supplied with grease through grease fittings 180 so that the bearing surfaces will be lubricated and so that the grease

pocket 178 will be disposed between the bearing surfaces and the joint 174. The interfitting arrangement of the shoulders on the rings 150 and 152 adjacent the grease pocket 178 provides a labyrinth effect between the joint 174 and the bearing surfaces.

In the modification shown in Fig. 8, a channel-shaped ring 200 is secured to the closure 24 by a series of bolts 202. The bearing ring 204 is bolted to the flange 206 of the hopper 208 by a series of bolts 210. In this case the hopper 208 is provided with a lip 212 which overhangs one edge 214 of the ring 200 and defines a joint 216 therebetween. The rings 200 and 204, along with the lip 212, provide a labyrinth effect 218 between the joint 216 and the bearing surfaces 220 and 222. In addition the rings 200 and 204 are formed to provide a series of grease pockets or grease channels 224, 226, 228 and 230 which may be supplied with grease through grease fittings in a manner similar to that shown in the previous modifications. In the case of Fig. 8, the thrust bearing surfaces 232 and 234 are also provided.

In the modification shown in Fig. 9 the ring 300 is secured to the closure 24 by a series of bolts 302, while the ring 304 is rigidly secured to the flange 306 of the hopper 308 by a series of bolts 310. The rings 300 and 304 are provided with interengageable cylindrical bearing surfaces 312, 314 and 316 and thrust bearing surfaces 318, 320, 322 and 324. A ring 326 is bolted to one face of the ring 300 by a series of bolts such as Allen head screws 328 before the ring 300 is bolted to the flange 306, and this ring 326 with the ring 35 which forms the flange 306 of the hopper forms one of the joints 330 of the bearing between the hopper 308 and the closure 24. The joint 330, like the joints 216 and 174 of the previous modifications, is a gap of the same size as that of the joint 30 and, like the joints 30, 174 and 216, is filled with grease for the purpose of excluding dirt from the bearing surfaces.

For the purpose of supplying grease to the joint 330 and grease to the grease channels or pockets 332 and 334, lubrication provisions of the type shown in Figs. 3 to 7 may be employed. The grease supplied to the joints exposed to the interior of the hopper in all of the modifications shown in this application, as well as to the other joints of the bearing which are exposed to the outside of the closure and the hopper, not only serves for lubrication purposes but also to exclude dirt and abrasive material from the bearing surfaces. It is desirable that these joints be well supplied with grease and frequently lubricated so as to flush out of the joints any dirt or foreign material which may contaminate the grease therein.

It will be observed in all of the modifications illustrated that the bearing surfaces comprise engageable cylindrical surfaces of substantial axial extent which are protected by grease channels and a labyrinth effect from the one joint which is exposed to the interior of the hopper, and that in all of the modifications shown the other of the joints between the hopper and the closure is exposed to the outside of the hopper and the closure. It will also be noted that each of the bearings includes thrust bearing surfaces for taking the axial thrust between the closure and the hopper and that these thrust bearing surfaces are likewise protected from the joint of the bearing which is exposed to the interior of the hopper.

While I have illustrated and described preferred embodiments of my invention, it is under-

stood that these are capable of modification and I therefore do not wish to be limited to the precise details set forth but desire to avail myself of such changes and alterations as fall within the purview of the following claims.

I claim:

1. In a concrete mixer having a rotatable mixing drum provided with an opening through which material is charged into and discharged from said drum, a closure engageable with said drum for sealing said opening and being rotatable with said drum when so engaged, said closure being movable away from said drum so as to permit the discharge of material therefrom through said opening, a material receiving hopper provided with a chute extending through said closure and into said drum through said opening when said closure is sealing said opening, said chute comprising a member carried by said closure and extending into said drum a substantial distance so as to charge material fed into said hopper into said drum at a distance inwardly away from said opening in said drum, means supporting said closure and hopper for movement away from and toward said drum, and means providing a bearing between said closure and hopper to permit relative rotation therebetween when said closure is rotating with said drum.

2. Apparatus according to claim 1 wherein said bearing means is constructed so that one of the joints thereof is exposed to the interior of said hopper and the other of the joints thereof is exposed to the outside of said hopper and closure.

3. In a concrete mixer having a rotatable mixing drum provided with an opening through which material is charged into and discharged from said drum, a closure engageable with said drum for sealing said opening and being rotatable with said drum when so engaged, said closure being movable away from said drum so as to permit the discharge of material therefrom through said opening, a material receiving hopper extending through said closure for charging material into said drum through said opening when said closure is sealing said opening, means supporting said closure and hopper for movement away from and toward said drum, and means providing a bearing between said closure and hopper to permit relative rotation therebetween when said closure is rotating with said drum, said bearing means comprising a ring fixed to said closure member for rotation therewith, a ring fixed to said hopper, said rings having interengageable annular axially extending bearing surfaces concentric with the axis of rotation of said drum, said rings being constructed and arranged and so secured to said closure member and hopper that one of the joints between said rings is exposed to the outside of said closure and hopper and the other of said joints is exposed to the interior of said hopper, said rings being constructed to provide a labyrinth effect providing a seal between said other of said joints and said bearing surfaces and a grease channel adjacent to said bearing surfaces.

4. In a concrete mixer having a rotatable mixing drum provided with an opening through which material is charged into and discharged from said drum, a closure engageable with said drum for sealing said opening and being rotatable with said drum when so engaged, said closure being movable away from said drum so as to permit the discharge of material therefrom through said opening, a material receiving hopper provided with a chute extending through

75 said closure and into said drum through said opening when said closure is sealing said opening, said chute comprising a member carried by said closure and extending into said drum a substantial distance so as to discharge material fed into said hopper into said drum at a distance inwardly away from said opening in said drum, means supporting said closure and hopper for movement away from and toward said drum, and means providing a bearing between said closure and hopper to permit relative rotation therebetween when said closure is rotating with said drum, said bearing means comprising a ring fixed to said closure member for rotation therewith, a ring fixed to said hopper, said rings having interengageable annular axially extending bearing surfaces concentric with the axis of rotation of said drum, said rings being constructed and arranged and so secured to said closure member and hopper that one of the joints between said rings is exposed to the outside of said closure and hopper and the other of said joints is exposed to the interior of said hopper.

5. Apparatus according to claim 4 wherein said rings are constructed to provide a labyrinth effect between said other of said joints and said bearing surfaces and wherein a grease channel is provided adjacent to said bearing surfaces.

6. In a concrete mixer having a rotatable mixing drum provided with an opening through which material is charged into and discharged from said drum, a closure engageable with said drum for sealing said opening and being rotatable with said drum when so engaged, said closure being movable away from said drum so as to permit the discharge of material therefrom through said opening, a material receiving hopper provided with a chute extending through said closure and into said drum through said opening when said closure is sealing said opening, said chute extending into said drum a substantial distance so as to charge material fed into said hopper into said drum at a distance inwardly away from said opening in said drum, means supporting said closure and hopper for movement away from and toward said drum, and means providing a bearing between said closure and hopper to permit relative rotation therebetween when said closure is rotating with said drum, said bearing means comprising a ring fixed to said closure member for rotation therewith, a ring fixed to said hopper, said rings having interengageable annular axially extending bearing surfaces concentric with the axis of rotation of said drum, said rings being constructed and arranged and so secured to said closure member and hopper that one of the joints between said rings is exposed to the outside of said closure and hopper and the other of said joints is exposed to the interior of said hopper, said joint exposed to the interior of said hopper comprising means defining a narrow gap filled with grease and opening from the inner wall of said hopper.

7. In a concrete mixer having a rotatable mixing drum provided with an opening through which material is charged into and discharged from said drum, an annular closure engageable with said drum for sealing said opening and being rotatable with said drum when so engaged, said closure being movable away from said drum so as to permit the discharge of material therefrom through said opening, a material receiving hopper on which said closure is rotatably mounted and adapted to charge material through

said opening in said closure and into said drum through the opening thereof when said closure is sealing said opening, means supporting said closure and hopper for movement away from and toward said drum, and means providing a bearing between said closure and hopper to permit relative rotation therebetween when said closure is rotating with said drum, said bearing means including a ring journalled on said hopper and forming a joint therewith remote from the discharge end of said hopper and on the inner wall of said hopper.

8. Apparatus according to claim 7 wherein said hopper is provided with a lip overhanging said joint.

9. Apparatus according to claim 7 wherein said ring is channel-shaped.

10. Apparatus according to claim 7 wherein said ring is channel-shaped and wherein the bearing surfaces between said hopper and ring are disposed within said channel-shaped ring.

11. In a concrete mixer having a rotatable mixing drum provided with an opening through which material is charged into and discharged from said drum, a closure engageable with said drum for sealing said opening and being rotatable with said drum when so engaged, said closure being movable away from said drum so as to permit the discharge of material therefrom through said opening, a material receiving hopper provided with a chute extending through said closure and into said drum through said opening when said closure is sealing said opening, said chute being carried by said closure and extending into said drum a substantial distance so as to charge material fed into said hopper into said drum at a distance inwardly away from said opening in said drum, means supporting said closure and hopper for movement away from and toward said drum, and means providing a bearing between said closure and hopper to permit relative rotation therebetween when said closure is rotating with said drum, said bearing means comprising a ring fixed to said closure member for rotation therewith, a ring fixed to said hopper, said rings having interengageable annular axially extending bearing surfaces concentric with the axis of rotation of said drum, said rings being constructed and arranged and so secured to said closure member and hopper that one of the joints between said rings is exposed to the outside of said closure and hopper and the other of said joints is exposed to the interior of said hopper, said rings being constructed to provide a labyrinth effect between said other of said joints and said bearing surfaces and a grease channel adjacent to said bearing surfaces.

12. In a concrete mixer having a rotatable mixing drum provided with an opening through which material is charged into and discharged from said drum, an annular closure engageable with said drum for sealing said opening and being rotatable with said drum when so engaged, said closure being movable away from said drum so as to permit the discharge of material therefrom through said opening, a material receiving hopper on which said closure is rotatably mounted and adapted to charge material through the opening in said closure and into said drum through the opening thereof when said closure is sealing said opening, means supporting said

closure and hopper for movement away from and toward said drum, and means providing a bearing between said closure and hopper to permit relative rotation therebetween when said closure is rotating with said drum, said bearing means including a ring journalled on said hopper and forming a joint therewith remote from the discharge end of said hopper and on the inner wall of said hopper, said bearing means having a joint exposed to the outside of said hopper and closure.

13. A concrete mixer having a charging hopper with a closure member rotatably carried by said hopper and a bearing between said closure and hopper, said bearing comprising a ring fixed to said closure for rotation therewith, a ring fixed to said hopper, said rings having interengageable cylindrical bearing surfaces and thrust bearing surfaces disposed transversely to said cylindrical bearing surfaces, said rings being constructed and arranged and so secured to said closure and hopper that one of the joints between said rings is exposed to the outside of said closure and hopper and the other of said joints is on the inner wall of said hopper.

14. A concrete mixer according to claim 13 wherein said rings are constructed to provide a labyrinth effect between said other joint and said bearing surfaces.

15. A concrete mixer according to claim 13 wherein one of said rings is channel-shaped in cross section and wherein the other of said rings is at least partially disposed in the recess provided by said channel-shaped section.

16. A concrete mixer according to claim 13 wherein each of said rings is secured to a sealing ring and wherein said sealing rings form a part of said hopper and are arranged in nesting relation with a narrow gap between adjacent portions thereof, said gap forming said other joint, one of said sealing rings being secured to said closure for rotation therewith and the other of said sealing rings being secured to said hopper.

17. A concrete mixer according to claim 13 wherein one of said rings comprises two separable parts secured together and defining an annular channel therebetween and wherein the other of said rings is provided with a portion running in said channel, said portion and said channel providing said thrust bearing surfaces.

18. A concrete mixer according to claim 13 wherein said closure member is secured to one of said rings and is provided with a portion arranged in overlapping relation with the other of said rings so as to secure said rings in assembled relation.

CHRIS GERST.
